J. DEVEY,

BEET TOPPING MACHINE.
APPLICATION FILED DEC. 18, 1918

UNITED STATES PATENT OFFICE.

JOHN DEVEY, OF LEHI, UTAH.

BEET-TOPPING MACHINE.

1,351,287.

Specification of Letters Patent. Patented Aug. 31, 1920.

Application filed December 18, 1918. Serial No. 267,312.

To all whom it may concern:

Be it known that I, JOHN DEVEY, a citizen of the United States, residing at Lehi, in the county of Utah and State of Utah, have 5 invented certain new and useful Improvements in Beet-Topping Machines; and I do hereby declare the following to be a full, clear, and exact description of the same, reference being had to the accompanying 10 drawings, forming part of this specification.

This invention relates to beet topping machines such as shown and described in my pending application Serial No. 221,026 and particularly to the means for regulating the height of the cutting disk which severs the tops of the beets. The regulating means disclosed in my prior application, while perfectly satisfactory for the purpose of regulating the height of the cutting disk when 20 the machine moves transversely of the row, has been found to be unsatisfactory in several other particulars. The more noticeable defect is that when the roller is elevated by coming in contact with an unusually large beet or a beet that protrudes quite some distance from the ground, the cutting disk is elevated the same distance as the roller, so that only a portion of the beet top is removed. Another defect is that when the 30 roller comes in contact with the beet whose body portion is a few inches out of the soil, the beet is pushed over, this being particularly true when the machine is operating on beets growing in loose soil.

The object of the present invention is to overcome these defects by providing means for regulating the height of the disk in such manner that the cutting disk is elevated only 40 a portion of the distance that the regulating member is elevated so that practically all of the top of the beet is removed, the regulating member also being of such character that all possibility of pushing the beet over 45 so that it will lie below the cutting disk is eliminated.

With these and other objects in view the invention consists in the improved construction and novel arrangement and combination 50 of the parts which will be hereinafter fully described and particularly pointed out in the appended claims.

In the accompanying drawings, wherein 55 is illustrated the preferred form of my invention:

Figure 1 is a side elevation, some of the

parts being shown in section, of a machine embodying the present invention;

Fig. 2 is a sectional view of the means for regulating the height of the cutting 60 disk.

Referring to the drawings, the main frame of the machine is composed primarily of upper and lower side members 2 and 1, each of the members 1 being offset inwardly at 65 1^a and their forward end portions carried forwardly as at 3, between which portions an ordinary tongue is secured in any suitable manner. Members 2 are secured at their front ends to members 1 and are supported at the rear ends by a brace or cross bar 4, the ends of which extend downwardly and are attached to members 1. A seat 5 is supported from cross bar 4 by a spring 6. Near their front ends members 1 are connected by a brace 7 and adjacent their rear ends 70 they are provided with the usual bearings for an axle 8, on the ends of which are mounted traction wheels 9.

A supplemental frame 10 is pivotally 80 mounted on axle 8 at a point in rear of its longitudinal center, its forward end dipping or swinging downwardly toward the ground.

Its rear end is provided with an extension 11 on which a counterbalance 12 is adjustably secured by a set screw 13 to permit the forward end of the frame to be more readily adjusted relatively to the ground.

A circular rotary cutting disk 14 is journaled on the front end of the supplemental 90 frame 10 by means of a cap screw 15 in position to be at an inclination to the ground when the frame is in normal position, the front portion of the periphery or cutting edge of the disk, which normally severs the 95 beet tops, being located at a point in close proximity to the ground and the side portions, which sever the beet tops when the machine moves transversely of the row of beets extending upwardly therefrom. The 100 disk receives its rotary motion from a bevel gear 16 rigidly mounted on axle 8, by means of a shaft 17 which is mounted in the body portion 18 of the supplemental frame and is provided with pinions 19, 20, at its opposite 105 ends which are adapted to mesh with the beveled gear 16 on the axle and a circular series of gear teeth on the under side of the disk, respectively.

At its forward end the supplemental frame 110 10 is provided on each side with a forwardly extending arch bar composed of two mem-

bers 21, 22, members 21 being secured to the frame and members 22 secured to members 21 by a pivotal connection, this type of connection being employed for a purpose which will presently appear.

Journaled in brackets 35 on the forward portion of the main frame is a transverse shaft 23 on which are mounted a pair of sprockets 24 spaced transversely of the shaft. Loosely mounted on said shaft and spaced transversely of the machine are two arms 25, the length of these arms being less than the distance between the cutting disk and the axle 8 for a purpose which will presently appear. The arms 25 are provided at their free ends with bearings for a shaft 26 which is adapted to support a pair of sprockets 27, similar to sprockets 24, in proximity to the cutting disk. These arms and sprockets constitute a belt frame on which an endless belt 28 is carried, the belt being driven from axle 8 by any suitable mechanism, but preferably by a sprocket chain 29 which passes over a sprocket gear 30 on the axle and a sprocket gear 31 on shaft 23, the sprocket gear on shaft 23 being of less diameter than that on the axle. With this arrangement of gearing the belt will travel over the sprockets at a greater rate of speed than the speed of the machine so that the tops of the beets will be gradually pushed down to the cutting disk, thus eliminating all possibility of pushing the beets over, as heretofore mentioned. The belt 28 may be of any suitable construction, but it preferably comprises cross pieces 32 that are bowed outwardly transversely of the belt to compensate for irregularities in the ground when the machine moves transversely of the row of beets.

Arms 25 are connected intermediate their ends by the forwardly extending arch members of the supplemental frame 10, the arch members normally being attached to the arms at a point which will permit the belt frame to assume a rearwardly inclined position with the rear end of belt 28 resting on the ground and in the same horizontal plane as the edge of the cutting disk. The rear lower end of the belt frame will remain in this position except when the belt comes in contact with a beet when it will, of course, be elevated. Owing to the difference in leverage of the supplemental frame and the arms 25, however, the cutting disk will not be raised as high as the rear end of the belt thus insuring the severance of practically all of the beet top. To permit the rear end of the belt to be adjusted vertically with respect to the cutting disk, the arms 25 are provided with a plurality of longitudinally spaced holes 36, thus permitting the arch members to be attached at any desired point in the length of the arms.

While the machine illustrated and described herein is adapted for topping only a single row of beets, it will be understood that the present invention may readily be utilized on machines capable of topping two or more rows without departing from the spirit of the invention.

What is claimed is:

1. In a beet topping machine, the combination with the main frame, of a vertically movable cutting disk, an elongated belt frame pivotally mounted adjacent one of its ends on the main frame with its opposite end in proximity to the surface of the ground, a traveling belt carried by the belt frame, and connections between the cutting disk and belt frame, whereby vertical movement of the belt frame will impart a vertical movement to the cutting disk.

2. In a beet topping machine, the combination with the main frame, of a cutting disk pivotally mounted on the main frame and adapted to be moved in a vertical plane, a belt frame pivotally mounted on a horizontal axis in the main frame, an endless belt movable on the belt frame adapted to engage the surface of the ground at a point remote from the pivotal point of the belt frame, the distance between the ground engaging portion of the belt and the pivotal point of the belt frame being less than the distance between the cutting disk and the pivotal point of the latter, and connections between the belt frame and the cutting disk whereby vertical movement of the belt frame will impart a vertical movement to the cutting disk.

3. In a beet topping machine, the combination with the main frame, of a cutting disk pivotally mounted on the main frame and adapted to be moved in a vertical plane, a belt frame pivotally mounted on a horizontal axis in the main frame, an endless belt movable on the belt frame adapted to engage the surface of the ground at a point remote from the pivotal point of the belt frame, the distance between the ground engaging portion of the belt and the pivotal point of the belt frame being less than the distance between the cutting disk and the pivotal point of the latter, connections between the belt frame and the cutting disk whereby vertical movement of the belt frame will impart a vertical movement to the cutting disk, and means for moving the belt on the belt frame at a rate of speed in excess of the speed of travel of the machine.

4. In a beet topping machine, the combination with the main frame having traction wheels mounted thereon, of a vertically movable cutting disk, an elongated belt frame pivotally mounted adjacent one end with its opposite end in proximity to the surface of the ground, a traveling belt carried by said belt frame, connections be-

5 tween the belt frame and cutting disk whereby vertical movement of the belt frame will impart a vertical movement to the cutting disk, and connections between the traction wheels and belt for driving the latter at a greater rate of speed than the machine.

10 5. In a beet topping machine, the combination with the main frame, a pivotally mounted supplemental frame adapted to be moved in a vertical plane, a cutting disk carried by the supplemental frame, a belt frame pivotally mounted on the main frame, an endless belt movable on the belt frame adapted to engage the surface of the ground at a point remote from the pivotal

20 point of the belt frame, the distance between the ground engaging portion of the belt and the pivotal point of the belt frame being less than the distance between the cutting disk and the pivotal point of the supplemental frame, and connections between the belt frame and supplemental frame whereby a vertical movement of the belt will impart a vertical movement of less degree to the supplemental frame, said connections between the belt frame and supplemental frame being adjustable to regulate the extent of movement of the supplemental frame and cutting disk.
